United States Patent Office.

ALGERNON L. WILKINSON, OF HUNTSVILLE, ALABAMA, AND ELIAS Y. BEGGS, OF NASHVILLE, TENNESSEE, ASSIGNEES TO ALGERNON L. WILKINSON.

Letters Patent No. 71,671, dated December 3, 1867.

IMPROVED PORTABLE HOSE-BRIDGE.

The Schedule referred to in these Letters Patent and making part of the same.

TO ALL WHOM IT MAY CONCERN:

Be it known that we, A. L. WILKINSON, of Huntsville, in the county of Madison, and State of Alabama, and ELIAS Y. BEGGS, of Nashville, in the county of Davidson, and State of Tennessee, have invented a new and useful Improved Portable Hose-Bridge for street-railroad cars; and we do hereby declare the following to be a full, clear, and exact description of the same, reference being had to the accompanying drawings, forming part of this specification, and in which—

Figure 1 is a cross-section,

Figure 2 is a side elevation, and

Figure 3 a top view of my bridge;

Figure 4 being an axial section of a portion of the cross-bar *o*, and

Figure 5 being a similar section showing the snap for confining the cross-bar in position.

Similar letters of reference indicate corresponding parts in the several figures.

The object of this invention is to furnish a neat, portable device by which hose lying across the track can be bridged over, so that the horses and cars will be enabled to pass it without inconvenience, and without damaging it.

In the drawings, *A A* represent the track of a common street-railway, and *H* hose lying across the rails. To enable cars to pass along the track while the hose is in this situation, I construct arched or double-inclined side pieces *B B*, of channel or angle-iron, beveling their ends so that they will fit closely down to the rails, and arching them at the middle just enough to clear ordinary hose. These arches are provided with at least two lugs, *c c*, on each side, projecting downward to bear against the sides of the rail, and hold the bridge in place. Each arch is provided also with at least two other lugs, *e e'*, projecting horizontally inward opposite to each other, the lugs *e* on one rail supporting a vertical socket, *i*, and those, *e'*, on the other, supporting the ends of cross-bars *o o*, which connect the arches. The ends of the cross-bars are simply bolted to the upper side of the lugs *e'* with round bolts, so that the cross-bars can be swung round, forward or backward, upon the bolts as a pivot. The opposite end of the cross-bars is provided with a goose-neck, *u*, attached to the bar by a swivel-joint, *v*, into one end of which the shank of the goose-neck is screwed. The goose-neck is designed to hook into the vertical sockets or eyes *i i*, and thus hold the arches firmly together. The length of the whole cross-bars can be adjusted easily, by means of the screws on goose-necks, to any gauge of track. The goose-necks may be provided with spring-snap catches *z z*, which will catch under the sockets or lugs and prevent the cross-bars from becoming detached from the arches by any vibration caused by the cars, or by any blow received from passing carriages or animals. Long, arched guards *G*, constructed of V-iron, or in the form of hollow semi-cylinders, may be laid over the hose between the arches to protect the pipes from injury by the horses' feet.

Having thus described my invention, what I claim as new, and desire to secure by Letters Patent, is—

The arches *B B*, when constructed of single pieces of angle or channel-iron, and provided with lugs *c c* to hold them to a railroad-track, in combination with the cross-bars *o o*, constructed with a swivel-link, *v*, and a goose-neck, *u*, substantially as and for the purpose indicated.

To the above specification of our improvement we have signed our hands, this 29th day of October, 1867.

A. L. WILKINSON,
E. Y. BEGGS.
